UNITED STATES PATENT OFFICE.

WILLIAM FULTON MELHUISH, JR., OF FARMINGDALE, NEW YORK.

DESIGN FOR A RADIATOR FOR AUTOMOBILES.

51,706.

Specification for Design.

Patented Jan. 22, 1918.

Application filed October 24, 1917. Serial No. 198,320. Term of patent 14 years.

To all whom it may concern:

Be it known that I, WILLIAM FULTON MELHUISH, Jr., citizen of the United States, residing at Farmingdale, Long Island, in the county of Suffolk and State of New York, have invented a new, original, and ornamental Design for a Radiator for Automobiles, of which the following is a specification, reference being had to the accompanying drawing, forming a part thereof.

In the drawing Figure 1 is a front eleva-

tion of a radiator for automobiles embodying my ornamental design, while Fig. 2 is a top plan view of the same.

I claim:

The ornamental design of a radiator for automobiles as shown.

WILLIAM FULTON MELHUISH, JR.

Witnesses:

WINFIELD S. PALMER,
E. E. VREELAND.
